Frederick Ronald Woodrow
INVENTOR:

By *Ottie Neumark*
his Attorney.

UNITED STATES PATENT OFFICE.

FREDERICK RONALD WOODROW, OF PINNAROO, SOUTH AUSTRALIA, AUSTRALIA.

TOOTHBRUSH.

Application filed August 1, 1924, Serial No. 729,478, and in Australia August 23, 1923.

My invention relates to improvements in tooth brushes, the object of the same being to provide a hygienic tooth brush which is constructed in such a manner that the brush portion can be thoroughly cleansed and will prevent the accumulation of foreign matter which at present takes place at the base of the tufts of bristles in tooth brushes of ordinary construction.

Hitherto it has been customary to make the tooth brush from one continuous piece of bone, ivory, celluloid, or similar material, holes being bored at one end thereof into which tufts of bristles are introduced and are held therein by cement, fine wire or other structural material.

The bristles of such brushes are arranged closely together and usually are assembled in three or more rows. Examination of such brushes after they have been in use for some time shows that foreign matter, principally of food stuff accumulates at the base of the bristles and not only forms a harbour for bacteria but also sets up a deterioration or rotting of the bristles which is intensified by the use of certain classes of dentifrice, particles of which also accumulate at the base of the bristles.

In order to overcome the disabilities above referred to instead of making the brush end in the manner previously described I form the base of the brush in separable parts or prongs, there being preferably three such parts in parallel arrangement, the base itself being detachable from the handle.

But in order that my invention may be more clearly understood I will now describe the same by aid of the accompanying illustrative drawings wherein:—

Fig. 1 is a side elevation of the tooth brush.

Fig. 2 is a plan of same with prongs fastened together with the clip.

Fig. 3 is a plan of tooth brush with prongs spread out to facilitate cleaning.

Fig. 4 is a modification of design of tooth brush.

Fig. 5 is an end view of brush.

Fig. 6 is a transverse sectional view through the prongs.

In each of the illustrations similar letters of reference are used to denote similar or corresponding parts wherever they occur.

In the drawings *a* is the butt end of the handle upon which one of the prongs, but preferably the middle prong *b* is permanently fastened or is made as an integral portion

of the handle. The end of this prong is increased in width by small extending wings *c* as clearly indicated in Figs. 3 and 5 which are adapted to support the free ends of the hinged prongs *d* and *e* which are pivoted to the handle by pins or pivots *f*, the arrangement being such that the prongs may be radially moved away from the centre part as shown in Fig. 3, and the prongs are of a somewhat semi-circular or triangular formation in cross section and are otherwise so constructed as to leave small spaces *g* and *h* between the fixed prong and the pivoted prongs.

Upon the fixed prong I attach a fastening clip *j* of any suitable design but in its preferred form it consists of a metal plate which is countersunk into the middle prong and securely fixed thereto by a brad or rivet *k*, the ends of the clip being adapted to fit neatly into countersunk recesses *l* and *m* formed in the pivoted arms and to slightly lap over the outer edges of said arms but without forming any appreciable projection.

The handle extension *n* may be either constructed as a continuous portion of the butt or may have a screw threaded hole bored therein for the accommodation of a dowel or of the screw threaded extension *o* of the butt so that interchangeable handles or butts may be used.

In arranging the bristles I place at the outer end of the brush a row of long bristles *p* which may be four in number, two of which are fitted to the broadened portion of the end of the fixed arm, and rearward of these bristles I insert a series of short bristles *q*, the bristles being fitted according to usual custom, that is to say, if the handle is of bone or metal grooves are formed in the back of the brush and holes are drilled through the brush so that bristles can be inserted through the holes and holding wires are accommodated within the grooves which are subsequently closed with filling material, but if the brush is formed of xylonite, celluloid, or the like the bristles are doubled together and the butt ends together with small binding rings or wires are punched into the material.

On reference to Fig. 1 of the drawings it will be seen that a space is left between the long end bristles and the first of the series of short bristles. This arrangement is intentional as it not only provides a suitable

space for the fastening clip but advantageously enables the long end bristles to be applied to the backs of the teeth with great freedom and without causing damage to the adjacent bristles.

In Fig. 4 I have shown a slight modification of the device but the basic principles of construction are similar to those already described, that is to say, there is a fixed prong *b* forming a portion of the butt of the handle and provided with a fastening clip or catch *j* and there is a hinged prong *d* adapted to fold in parallel arrangement with the fixed prong and when so folded a space is left between the adjacent members.

When applied to practical use the prongs are placed in the position indicated in Fig. 2 and the brush may then be applied for the purposes of cleaning the teeth. The slots primarily prevent an accumulation of foreign matter at the base of the bristles and after the cleaning operation has been completed the hinged prongs swing away from the fixed portion and the cleaning of the roots of the bristles is easily effected. The brushes may be constructed in various sizes according to requirements and the handles may be standardized so that the same handle may be used for a number of brushes.

One of the parts may be an integral portion of the handle or of the butt of the han-

dle and can with advantage be from one eighth of an inch to a quarter of an inch in width and is preferably bevelled along the sides so that it is somewhat semi-circular or triangular in formation in cross section.

This formation is not essential but I prefer that the outer edges or prongs which are hinged to the butt end of the handle should be slightly rounded to facilitate the arrangement of a fastening clip, the prongs being suitably hinged to allow them to be spread open, and the butt of the handle may be furnished with a screw threaded portion to enable interchangeable ends or handles to be used.

I claim:

In a tooth brush of the character described, the combination of a plurality of separable units having rows of tufts of bristles, each row thereof having a space adjacent the outer end and disposed between the outermost tuft of bristles and the next adjacent tuft of bristles, the length of the outer tuft of bristles being longer than the next adjacent tuft, and means carried by one of said units in the said space and adapted to engage over the other units in the corresponding spaces.

In testimony whereof I have affixed my signature.

FREDERICK RONALD WOODROW.
